(57) CLAIM

The ornamental design for an ankle wallet as shown and described.

DESCRIPTION

FIG. 1 is an isometric front view of the ankle wallet, which embodies the presently disclosed design;

FIG. 2 is an isometric back view thereof;

FIG. 3 is a front view thereof;

FIG. 4 is a back view thereof;

FIG. 5 is a bottom view thereof;

FIG. 6 is a top view thereof;

FIG. 7 is a left view thereof;

FIG. 8 is a right view thereof; and,

FIG. 9 is a diagram showing how the ankle wallet can wrap around a user's ankle.

Portions of the drawings shown in broken lines in FIGS. 1-8 indicate stitches in the design. Portions of the drawings shown in broken lines in FIG. 9 form no part of the design, except for those indicating stitches as illustrated by FIGS. 1-8.

1 Claim, 5 Drawing Sheets
